UNITED STATES PATENT OFFICE

147,572

DESIGN FOR A HANDBAG OR SIMILAR ARTICLE

Arthur H. Witmondt, New York, N. Y.

Application February 1, 1947, Serial No. 136,627

Term of patent 3½ years

(Cl. D87—3)

To all whom it may concern:

Be it known that I, Arthur H. Witmondt, a citizen of the United States of America, residing in New York city, county of New York, and State of New York, have invented a new, original, and ornamental design for a Handbag or Similar Article, of which the following is a specification, reference being had to the accompanying drawing, forming part thereof, wherein,

I claim:

The ornamental design for a handbag or similar article, substantially as shown and described.

ARTHUR H. WITMONDT.
